HAIR CURLER OR SIMILAR ARTICLE

Eugene Buzasi, Sunnyside, N. Y., assignor to Sara Hering, New York, N. Y.

Application October 29, 1951, Serial No. 17,158

Term of patent 14 years

(Cl. D86—10)

To all whom it may concern:

Be it known that I, Eugene Buzasi, a citizen of the United States of America, residing in Sunnyside, New York, county of Queens, and State of New York, have invented a new, original, and ornamental Design for a Hair Curler or Similar Article, of which the following is a specification, reference being had to the accompanying drawing, forming part thereof, wherein:

The sides and rear of the design are identical in appearance to the side shown in Figure 1.

I claim:

The ornamental design for a hair curler or similar article, substantially as shown and described.

EUGENE BUZASI.
